UNITED STATES PATENT OFFICE.

LORENZO HOLTSLANDER, OF OBERLIN, OHIO.

MARINE PROPELLER.

Specification of Letters Patent No. 25,336, dated September 6, 1859.

To all whom it may concern:

Be it known that I, LORENZO HOLTS-
LANDER, of Oberlin, county of Lorain, and
State of Ohio, have invented a new and use-
5 ful Improvement on the Machinery Used
for Propelling Vessels or Boats by Water
Propulsion; and I do hereby declare that
the following is substantially a full and ex-
act description of the same, reference being
10 had to the drawings hereto attached, making
a part of this specification, in which—

Figure No. 1 is a perspective view, and
Nos. 2 and 3 sectional parts thereof.

The nature of my invention consists in a
15 device to change the location of the valves
and valve seats of a water propeller or
pump, used for water propulsion, and thus
reverse the motion of a vessel and the com-
bination, forward, or in the bows, of a res-
20 ervoir and several small pipes through
which a supply of water is obtained for the
propellers.

To enable others skilled in mechanics to
make and use my invention, I will proceed
25 to describe its construction and operation.

I use the double seated valve box (B Fig.
No. 3 in drawings attached) with a ball
valve (V) made of metal, hollow, and
strong enough for my purpose. The valve
30 box (B) is made a little deeper than would
ordinarily be necessary with valve seats in
two, opposite sides. I use a movable grate
(G) or false bottom, for the valve to travel
on, which grate is kept in place by a pro-
35 jection from each corner of the grate, which
work in angular or arc slots (S) Fig. 3, in
the two sides of the valve box (B) which
are in juxtaposition to the sides in which
are the valve seats. I elevate either end of
40 the grate, desired, by the rods (R, R,) which
pass through the bottom of the valve
box (B), and a packing box if necessary,
vertically and which are operated by a lever
(L) whose fulcrum (F) is placed so as to
45 give equal motion to the rods operating the
grate (G). The connection of the rods
(R, R,) with the lever (L) is by means of
a slot joint to give a motion to the rods
(R, R) at right angles with the bottom of
50 the valve box (B). It will be seen that as
the extended end of the lever (L) is ele-

vated or depressed, it by the rods elevates
one or the other ends of the grate (G) and
when either end of the grate is above the
lower edge of its neighboring valve seat, the
55 valve cannot find that seat but readily finds
the opposite one. In attaching these valve
boxes to a propeller, as in Fig. No. 2, whose
four valve boxes are attached to constitute
with the cylinder a single cylinder double
60 action, suction and force propeller, I make
one valve seat the immediate passage to the
cylinder and the other the passage to the
connecting pipe, then by any convenient ar-
rangement I connect the valve box levers 65
to one lever, so that a single motion will
change all the valve seats of a propeller, be-
ing careful that the levers of the valve boxes
on either side of a propeller are parallel to
each other, making one side the supply side 70
and the other the discharge side.

In obtaining a supply of water for pro-
pelling vessels or boats by water propulsion
I place forward in the bows of the vessel a
reservoir (Rv. Fig. No. 1) capable of hold-
ing water enough to supply two or three
75 strokes of the propeller, which I supply
through several small pipes (p p p p)
connecting with the reservoir and passing
through the bows, in different directions, 80
below the water line. These small pipes
should be numerous enough to provide the
reservoir with a generous supply of water.

The reservoir and propellers I connect
with the usual supply pipe. The small pipes 85
will prevent obstructions reaching the
valves. Reservoir, pipes, valve boxes and all
parts should be constructed sufficiently
strong to perform the work required.

What I claim as new and wish to secure 90
by Letters Patent, is—

The device, herein described, for chang-
ing valve seats as applied to water-pro-
pellers, to reverse the motion of vessels or
boats, and also the combination of the small 95
forward pipes (p p p p) with the reservoir
(Rv.) substantially as described.

LORENZO HOLTSLANDER.
